UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,307,641.

Specification of Letters Patent. Patented June 24, 1919.

Application filed May 14, 1918. Serial No. 234,417.

To all whom it may concern:

Be it known that I, JESSE A. B. SMITH, a citizen of the United States, residing in Stamford, in the county of Fairfield and 5 State of Connecticut, have invented certain new and useful Improvements in Type-Writing Machines, of which the following is a specification.

This invention relates to typewriting machines, and is illustrated in connection with a so-called fan-fold typewriting machine of the Underwood type embodying improvements shown in the patent to Wernery and Smith, No. 1,132,055. The machine herein disclosed also embodies certain of the features shown in my co-pending application, Serial No. 151,888, filed March 2, 1917 (now Patent No. 1,281,087, dated October 8, 1918).

In such machines, the typewriter platen 20 is adapted to be swung up clear of the usual feed rolls, which normally coöperate with it, to permit a web or work-sheet to be drawn forwardly beneath the platen in substantially a straight line, in order to 25 enable a work-sheet to be cut off by a knife clear of the carbon sheets used in writing the carbon copies thereof. This cutting off is usually done by drawing the sheet against a fixed or movable knife while the 30 sheet is held by the usual feed rolls, the platen having been swung into place to hold the work-sheet against the feed rolls. An object of the invention is to provide for even and neat severing of the web, even 35 when it is of unusually tough paper.

In order to enable this cutting to be accurately and cleanly effected more rapidly and conveniently than has heretofore been possible, I provide a clamp which is adapted 40 to firmly hold the web against a solid part of the carriage, while a section is being severed, thus preventing any possibility of slipping of the work-sheet around the platen at the severing operation, thereby 45 insuring that the new edge will be smooth and true. This latter object is especially desirable when the work-sheets are used as letters, or other documents, to be sent to customers, especially if written on lined 50 paper, or in the nature of forms which are filled out along predetermined lines. By positively detaining the work-sheet while being torn, it is possible to have a tear which will be so clear and straight that the customer receiving the written-out work-sheet

will be impressed with its neatness, and not be offended by the untidy appearance of any irregular edge thereon, such as has hitherto militated against sending such work-sheets to customers in the form of letters or invoices. 60

Other features and advantages will hereinafter appear.

In the accompanying drawings.

Figure 1 is a fragmentary perspective 65 view of so much of an Underwood typewriting machine, embodying my invention, as will illustrate some of the utilities thereof.

Fig. 2 is a sectional side view of the same, showing the holding bar ineffective. 70

Fig. 3 is a view similar to Fig. 2, but showing a work-sheet being severed, and the main body of the web being held by the holding bar.

Fig. 4 is a view similar to Fig. 3, but 75 shows how the invention may be applied advantageously to one form of machine now in use.

In the Underwood fan-fold typewriting machine disclosed in said patent to Wernery and Smith, type-bars 10 strike against the front side of a platen 11, of which the axle 12 is journaled in end plates 13 of a frame, the latter hinged on a transverse rod 14 at the front of the typewriter carriage. 80 The work-sheet 15 is usually in the form of a fan-fold web having several plies which are passed down over a paper table 16 at the rear of the platen, then under the platen past feed rolls 17 and 18, and up past the 85 front side of the platen beyond a knife 19 onto a front paper table 20.

The work-sheet 15 is advanced around the platen by operating the usual line-space handle 21, which is effective to rotate said 90 platen through a pinion 22 meshing with an idler 23 journaled on the shaft or rod 14, which idler in turn meshes with a pinion 24 fast on the platen axle, substantially as shown in said patent to Wernery and Smith. 100

When a work-form has been filled out and it is desired to detach the filled-out form 25 from the web 15, the platen is swung to its upper position, as described in said patent, the end of the web being drawn against the 105 adjustable end gage 26 on the end of a support 27, while the side of the web is gaged against the side gage 28. The platen is usually then swung back into place, so that the web 15 is gripped fairly firmly between the 110

feed rolls 17 and 18 and the platen 11, and then the filled-out form 25 is detached from the body of the web by drawing it against the knife 19 lying along the platen, as indicated in Fig. 3.

Where the web comprises a considerable number of plies, or where the web is of a somewhat slippery material, or is of paper difficult to sever, there is apt to be slipping of the web during the severing operation, with the result that instead of showing a straight edge, or an edge at right angles to the edge of the web, the severed work-sheet may show a curved edge, or one running at an angle to the work-sheet. To prevent this slipping, I utilize the flat surface forming the upper part of the paper table 16 as a gripping surface by providing a gripping or holding plate 31 adapted to hold the web at the edge from which the cutting starts.

For convenience, the plate 31 may be in the form of a flat bail or bar mounted to swing in brackets 32 at the opposite ends of the paper-table 16. To enable it to be mounted in this way, the plate 31 may be mounted on rock arms 33 fast on the shaft 34, said shaft being journaled in the brackets 32. To swing the gripping plate 31 to effective position, there may be fast to the shaft 34 a finger-piece 35 extending upwardly from the shaft and formed as an extension of one of the arms 33. This finger-piece 35 may be drawn forward in Fig. 1 by the left-hand thumb or finger of the operative, to carry the holding plate 31 rearwardly against the paper table 16 against the tension of the spring 36 which encircles the shaft 34 and normally holds the gripping plate 31 clear of the paper table 16. When a work-sheet is thus gripped, as illustrated in Fig. 3, the operative may tear off the work-sheet 25 by grasping said work-sheet with the right hand at the upper left-hand corner 37 and pulling it so as to tear it against the edge of the knife 19.

In order to enable the gripping plate 31 to get a firm hold on the work-sheets, the gripping face thereof may be knurled or provided with file-teeth of such a nature that they will not mar the appearance of the front or outside ply of the webs. This is not difficult of accomplishment, because the knurled face 38 presses the web against the flat metal surface of the paper table 16, with the result that although the projections of the knurled surface will make an imprint on the sheet or ply against which they directly lie, they will make little or no imprint on other plies which are protected by the ply against which the knurled face actually bears.

By having the gripping plate 31, the necessity is avoided of having a very close fit between the pin 39 and the latch 40, which is usually depended on to hold the

platen 11 firmly enough against the feed rolls 17 and 18 to keep the web from slipping. This avoiding of a close fit between the pin 39 and the latch 40 enables said latch and pin to be so shaped that they will engage each other more certainly and rapidly than would otherwise be possible.

In order to prevent the plate 31 from being swung too high and to prevent rattling, there is provided a fixed pin 41 against which the spring 36 will normally hold the lug 42, thereby holding the plate 31 clear of the table 16 and at its most convenient position for the insertion of new webs.

In Figs. 1, 2 and 3, the gripping plate 31 is illustrated as applied to a machine embodying the knife, described and claimed in my prior application No. 217,302, filed February 15, 1918, and to a machine which has a flat table 16 running upwardly from the rear feed roll 17.

Many fan-fold machines are of the type shown in Fig. 4, wherein the rear paper table 16 is provided with a steep portion 43 near the upper end thereof, and a less steep portion 44 at the lower portion thereof. In this form of machine, it may be found preferable to place the gripping plate 31 rearwardly of a shaft 45 which corresponds in every way to the shaft 34, except that it lies nearer the front paper table 20. This brings the gripping plate 31 to the position where it grips horizontally against a flat portion 46, extending rearwardly from the upper portion of the paper table 16, thereby enabling the gripping plate to get, in effect, a stronger hold on the webs 15, since the webs turn the corner 47 between the gripping plate 31 and the platen 11. Where this form of construction is used, the arms 48, on which the gripping plate is carried in Fig. 4, are nearly horizontal arms, and the finger-piece 49, by which the gripping plate is made effective, is moved rearwardly instead of forwardly. Consequently, the spring 36 (not shown in Fig. 4) will in said figure be effective in the reverse direction, and a pin 50, corresponding in function to the pin 41, lies on the opposite side of the lug 42 to hold the gripping plate in its normal position.

Variations may be resorted to within the scope of the invention, and portions of the improvements may be used without others.

Having thus described my invention, I claim:

1. In a typewriting machine, the combination with a revoluble platen, of a paper-table at the introductory side of said platen, a knife at the delivery side of said platen, against which a web may be drawn to be severed, and a device to grip the web against the paper-table to hold the web while the front portion thereof is being severed by the knife.

2. In a typewriting machine, the combi-

5 nation with a revoluble platen and feed-rolls adapted to hold a web against the platen, of a knife beyond said platen adapted to sever sections from the web, and a gripping device including a finger-piece adapted to make it effective to grip the edge of the web to enable a section to be torn off evenly from said web.

10 3. In a typewriting machine, the combination with a revoluble platen and feed-rolls adapted to hold a web against said platen, of a paper-table, a knife beyond said platen against which the web may be drawn so that sections may be torn off, a gripping 15 device behind the platen adapted to coöperate with the paper-table in holding the web, and a finger-piece adapted to make said gripping device effective.

20 4. In a typewriting machine, the combination with a revoluble platen, of a paper-table adapted to deliver a web behind said platen, a knife beyond said platen against which said web may be drawn to be torn off, a device having a knurled surface, and a 25 finger-piece adapted to grip the web by said surface to hold the web while the front portion thereof is being torn off.

30 5. In a typewriting machine, the combination with a revoluble platen, of a paper-table adapted to deliver a web behind said platen, a knife beyond said platen by which said web may be torn off, a gripping plate 35 extending across said table adapted to grip the web against the paper-table to hold the web while the front portion thereof is being torn off by the knife, and a finger-piece for making the gripping plate effective.

40 6. In a typewriting machine, the combination with a revoluble platen, of a paper-table adapted to deliver a web behind said platen, a knife beyond said platen against which said web may be drawn to be torn off, an extension of said paper-table forming an 45 angle therewith, about which angle said web turns, a gripping plate adapted to grip the edge of the web against said extension to hold the web while the front portion thereof is being torn off, and a finger-piece for 50 making said gripping plate effective.

7. In a typewriting machine, the combination with a revoluble platen, of a paper-

table adapted to deliver a web behind said platen, a knife beyond the platen against which the web may be drawn to be torn off, 55 an extension of said paper-table forming an angle therewith, around which angle the web turns fairly sharply, a gripping device adapted to grip the left-hand edge of the web to hold the web while the front portion 60 thereof is being torn off by the knife, and a finger-piece adapted to be operated by the left hand of the operator to make the gripping device effective.

8. In a typewriting machine, the combination with a revoluble platen, of a paper-table adapted to deliver a web behind said platen, a knife beyond said platen against which said web may be drawn to be torn off, a bail extending across said paper-table 70 forming a gripping member adapted to grip the web against the paper-table, brackets in which said bail is mounted, a spring normally holding it clear of the paper-table, and a finger-piece for making it effective to grip 75 the web.

9. In a typewriting machine, the combination with a revoluble platen, of a paper-table adapted to deliver a web behind said platen, a knife beyond said platen 80 against which said web may be drawn to be torn off, an extension of said table forming a fairly sharp angle with the rest of the table, a bail extending across the length of said extension having a surface 85 adapted to grip the web against the extension, a shaft on which said bail is mounted, a spring normally effective to hold the bail clear of the extension, and a finger-piece for making the bail effective to grip the web. 90

10. In a typewriting machine, the combination with a revoluble platen, and means to feed a web around the same, of a web-severing knife at the delivery side of the platen, and normally ineffective manually-operable means to engage the web to detain it while it is being severed by means of the knife, said detaining means being mounted to engage the web at the introductory side of the machine in rear of the platen. 95
